ATTORNEY

UNITED STATES PATENT OFFICE.

WARREN F. KAYNOR, OF WATERBURY, CONNECTICUT, ASSIGNOR TO WATERBURY
BUTTON COMPANY, A CORPORATION OF CONNECTICUT.

CAP BUTTON.

Application filed September 8, 1921. Serial No. 499,297.

To all whom it may concern:

Be it known that I, WARREN F. KAYNOR, a citizen of the United States, and a resident of Waterbury, county of New Haven, 5 and State of Connecticut, have invented certain new and useful Improvements in Cap Buttons, of which the following is a specification.

This invention relates to cap-buttons such 10 as are used on uniform caps for attaching the ends of the extensible leather straps, commonly worn above the visors of such caps.

One object of the invention is to produce 15 a uniform cap-button of this type in which the button shank may be rigidly secured to the head of the button, without the use of solder.

Another object is to produce a uniform 20 cap-button of this type in which the button shank will be supported upon the button back with a high degree of stability, and in which a portion of the button shank itself is utilized to positively space the button- 25 shell from the button-back.

A further object is to produce a uniform cap-button of this type which will be of simple construction, cheap to manufacture, strong, and durable in use.

30 With the above and other objects in view, there have been illustrated in the accompanying drawings, several forms in which the invention may be conveniently embodied in practice.

35 Fig. 1 is a perspective view of a uniform cap showing the extensible leather strap and a cap-button in position.

Fig. 2 is a top view of the shell of a cap- 40 button.

Fig. 3 is a sectional view of one embodiment of the invention showing the shell, the back and the shank of a button in their relative positions.

Fig. 4 is a top plan view, with the shell 45 removed, of the button shown in Fig. 3.

Fig. 5 is a perspective view of the button-shank shown in Figs. 3 and 4—detached from the remainder of the button.

50 Fig. 6 is a sectional view taken along the line 6—6 of Fig. 1, illustrating the two wire prongs of the button-shank projecting through one end of the extensible leather strap, and the cap fabric.

55 Fig. 7 is a top view of a modified form of shank.

Fig. 8 is a perspective view of the shank 60 illustrated in Fig. 7.

Figs. 9 and 10 are top and perspective views respectively, of another modified form of shank.

Figs. 11 and 12 are top and perspective views respectively, of a still further modified form of shank.

Referring now to the drawings in which like numerals denote corresponding parts 65 throughout the several views; the body or head of the cap-button is composed of a flanged circular disc or "back" 10, and a face or cylindrical "shell" 11. The shell 11 may be secured to the back 10 in any 70 suitable manner, preferably by swaging the annular bead 12, of the shell around the upstanding flange 13 on the periphery of the back 10.

The head of the button is secured to the 75 uniform cap by means of a wire shank which—in the preferred form illustrated in Figs. 3 to 6—has a looped 8-shaped configuration, in plan view.

As clearly shown in Figs. 3 to 6, the loop 80 of the U-shaped wire shank, located within the head of the button, is provided with three horizontal flat curved sections 14, 15, 16, in contact with the back 10 to stabilize the shank in all directions, so that its 85 downwardly projecting prongs 17, 17—which extend through the openings 18, 18 in the back—will be perpendicular to the plane of the back. The curved sections 14, 15, 16 are connected by the raised sections 90 19, 20, parallel with the prongs 17, 17—and forming contacts for the shell to positively space it from the back. It will thus be seen that the shank-loop between the shell and the back is quite rigid and will resist 95 stresses from all directions. There are three contacts with the back and two with the shell.

In operation, when it is desired to attach the extensible strap to the cap, the prongs 100 17, 17 of the shank are first inserted through holes in the leather strap 21 and in the fabric 22 of the cap 23. The prongs 17, 17 are then bent over at right angles, as clearly shown at 24, 24 in Fig. 6, so that they will 105 lie in a straight line just inside the cap, between the fabric 22 and the lining.

Any desired insignia, emblem, or design may be placed upon or formed in the metal of the shell 11. Moreover, the shell, the 110

back, and the shank may be made of any desired size and shape and of any suitable material.

In the modified form of shank shown in Figs. 7 and 8, the wire loop is substantially circular in plan view, and is provided with four horizontal flat back-engaging sections 25, 25 26, 26, perpendicular to the prongs 17, 17. The radial sections 25, 25 are connected with the sections 26, 26 by the raised sections 27, 28, 29 which form three equidistant contact points for the shell 11. As will be seen there are four contacts with the back and three with the shell.

In the modified form of shank illustrated in Figs. 9 and 10, the shank loop is substantially circular in plan view—being similar in this respect to the device illustrated in Figs. 7 and 8. The back-contacts, 30 and 31 as well as the shell-contacts 32 and 33, form right angles with one another. This construction gives a high degree of stability and strength with only two contacts with the back and three with the shell.

Another modified form of the invention is illustrated in Figs. 11 and 12. In this embodiment, the shank is provided with a loop having the form of a spiral in plan view. This spiral loop has two portions 34 and 35 in contact with the back connected by the raised shell contacts 36 and 37, the latter contacts being perpendicular to each other.

It will be obvious that with each form of improved cap-button disclosed, the shank is permanently locked or anchored to the head, and cannot be dislodged from the button back, no matter how much rough handling it may receive.

Moreover, in each embodiment, the shank is provided with a plurality of sections in contact with the back, and a plurality of raised sections in contact with the shell—thus stabilizing the shank, and positively spacing the shell from the back.

While there have been disclosed in this specification, several forms in which the invention may be embodied, it is to be understood that these forms are shown for the purpose of illustration only; and that the invention is not to be limited to the specific disclosures but may be modified and embodied in various other forms without departing from its spirit; in short, the invention includes all the modifications and embodiments coming within the scope of the following claims.

Having thus fully described the invention, what is claimed as new, and for which it is desired to secure Letters Patent, is:

1. In a uniform cap-button, a back, a shell, and a wire shank having a looped portion located between the back and the shell, said shank serving to positively space the shell from the back.

2. In a uniform cap-button, a back, a

shell crimped thereon, and a wire shank for securing the button to a cap and for spacing the shell from the back.

3. In a uniform cap-button, a back, a shell, means for securing the shell to the back, and a looped wire located between the shell and the back for spacing the shell and back from one another.

4. In a uniform cap-button, a back, a shell, and a shank having a portion located between the shell and back for spacing the shell from the back, said shank being provided with a pair of cylindrical prongs.

5. In a uniform cap-button, a back, a shell, and a wire shank having a portion located between the shell and back for spacing the shell from the back.

6. In a uniform cap-button, a back, a shell, a substantially U-shaped wire shank looped through openings in said back for attaching said button to a cap, the curved end of the U-shaped shank being located between the shell and back, and having a side section engaging the back, and an upper raised section engaging the shell.

7. In a uniform cap-button, a back, a shell, a wire shank looped through a pair of openings in the back, the looped portion of the shank comprising a flat stabilizing section in contact with the back and a raised section in contact with the shell.

8. In a uniform cap-button, a back, a shell crimped thereon, a wire shank looped through said back, the looped portion of said shank comprising a plurality of shank-stabilizing sections in contact with the back, and a plurality of raised shell-spacing sections in contact with the shell.

9. In a uniform cap-button, a back, a shell, a U-shaped wire shank looped through openings in the back, said shank having a pair of parallel prongs adapted to be passed through a leather strap and the fabric of a cap, the looped portion of said shank having a section in contact with the back and a raised section in contact with the shell.

10. In a uniform cap-button, a back, a shell, and a wire shank for securing the button to the fabric of the cap, said shank comprising two parallel prongs connected by a looped portion, said looped portion serving to space said back from said shell, said looped portion having a section parallel to said shank.

11. In a uniform cap-button, a back, a shell, and a wire shank for securing the button to the fabric of the cap, said shank comprising two parallel prongs connected by a looped portion, said looped portion serving to space said back from said shell, and having a perpendicular shank-stabilizing section in contact with the back.

12. In a wire shank for a uniform cap-button, a pair of parallel prongs, a flat stabilizing portion lying in a plane perpen-

dicular to said prongs and adapted to contact with the button-back, and a raised portion parallel with said prongs adapted to contact with the button-shell, to positively 5 space it from the button-back.

13. In a uniform cap-button, a back, a shell, and a wire shank having a looped portion located between the back and the shell for stabilizing the shank and positively 10 spacing the shell from the back, said looped portion having the configuration in plan view of a figure 8.

14. In a uniform cap-button, a back, a shell, and a shank having a looped portion 15 located between the back and the shell for stabilizing the shank and positively spacing the shell from the back, said looped portion having the configuration in plan view of a figure 8, the end sections of the 20 looped portion being raised to contact with

the shell and the central sections lying in contact with the back.

15. In a uniform cap button, a back, a shell, and a wire shank having a looped section located between said back and said shell, said looped section serving to positively 25 space said shell from said back and to stabilize said shank, said looped section having a portion parallel to said shank, and a portion at right angles to said shank.

16. In a uniform cap button, a back, a shell, a shank for attaching said button to a strap on the uniform cap, said shank having a plurality of loops located between said back and said shell for stabilizing said 30 shank and positively spacing said shell from said back.

In testimony whereof, I have affixed my signature to this specification.

WARREN F. KAYNOR.
